UNITED STATES PATENT OFFICE.

ARCHIBALD G. LAMONT, OF CLARKSBURG, WEST VIRGINIA.

FLYING-MACHINE.

1,305,555.

Specification of Letters Patent.

Patented June 3, 1919.

Application filed February 26, 1917. Serial No. 151,930.

To all whom it may concern:

Be it known that I, ARCHIBALD G. LAMONT, a citizen of the United States, residing at Clarksburg, in the county of Harrison and State of West Virginia, have invented certain new and useful Improvements in Flying-Machines, being a combination of the aeroplane and the lighter-than-air type, of which the following is a full specification.

10 This invention relates to new and useful improvements in flying machines for air navigation and consists of new and novel construction and combination of parts designed to give great buoyancy to the machine and safety while navigating the air, descending, and landing upon land or water as hereinafter described and claimed.

15 The main object of my invention is the production of a flying machine constructed of metal and other suitable combination of materials, and having means by which the operator shall have absolute control of said flying machine while navigating the air or when descending, and in case of accident to 20 the motor power the rapidity of descent could be retarded to the minimum and fully under the control of the operator.

25 Another object is to provide means within the said flying machine by which it would maintain its equilibrium while in the air and land easily and safely upon the surface of land or water.

30 A further object is to generally improve this class of flying machines, with the view to increase the carrying capacity and reducing the size of the machine, thereby rendering them of more general use, safe, and commercially desirable.

35 With these and other objects in view as will more fully appear as the description proceeds, it will be observed that my invention may be constructed of any combination of suitable materials and consists of certain novel, mechanical devices and combination 40 of parts as hereinafter fully described, illustrated and claimed, it being understood that several changes may be made in the construction as here described without departing from the spirit and intent thereof; reference being had to the accompanying drawings in which:—

45 Figure 1 represents a side elevation of the complete flying machine, minus the motor power and propelling devices.

50 Fig. 2 represents a longitudinal vertical section along the dotted line $b-b$, (Fig. 4,)

showing the main gas cylinder, three air cylinders within, exhaust chamber on top, and the location of the motor power, propeller wheels and connections.

55 Fig. 3, represents a front end view of the complete machine showing the end of the gas cylinder and the air flues within and near the center of which the propeller wheels are operated.

60 Fig. 4, is a vertical cross section of the flying machine along the dotted line $a-a$, see Fig. 1.

65 Fig. 5, represents a detached side elevation of the front steering planes showing the connections by means of which they are tilted, at the will of the operator.

70 Referring to the drawings similar numerals and letters refer to similar parts throughout the several views.

75 The numeral 1 designates the skeleton frame work constructed of tubing or other suitable material consisting of longitudinal vertical and angular rods and strips securely fastened together at their intersecting points; numeral 2 designates a large air tight cylinder constituting a gas chamber to the bottom and ends of which the skeleton frame work is securely braced and fastened. 3, designates the outer casing of 80 the exhaust chamber having sloping ends and which entirely covers, and is riveted to the upper half of the gas cylinder. 4, designates the exhaust chamber into which the exhaust and hot air from the gas engines 85 are discharged and by means of which added buoyancy is obtained to the machine. 4', designates release valves securely attached to the upper portion and at each 90 end of the exhaust chamber, and by means of which excessive pressure within the exhaust chamber may be released. 5 designates the two swinging air gates which are securely hinged and cushioned close to the 95 sides of the main gas cylinder, one on each 100 side by means of hinges 5'. The outer edge of the said air gates rest and are cushioned tightly against the inner surface of the outer case of the exhaust chamber. 6, designates the space within the large main gas 105 cylinder and around the air flues into which space special gas is forced, and by means of which great buoyancy is obtained for the machine. 7, designates the concave front 110 head or end of the main gas cylinder, and 7' designates the straight rear end of the gas cylinder. Numerals 8 represent three open

air flues within the gas cylinder in close relation to each other and extending longitudinally from end to end of the main gas cylinder and are securely fastened to the 5 ends of said cylinder. Numeral 9 designates open air space of the air flues 8 within which flues and near the center thereof are mounted propeller wheels. Numeral 10 is the gas engine having transmission shaft 10'. Numerals 11, 11', and 11'', represent 10 vertical shafts which transmit the power from the engine shaft 10' to the propeller wheels 14, 14', and 14'' which are mounted and revolve within and near the center of 15 their respective air flues. 12, designates fuel tanks from which fuel is supplied to the gas engine. 13 and 13' designate worm gears by means of which motion is transmitted from the engine shaft to the vertical 20 shafts. Numerals 15, 15' and 15'' designate bevel gear wheels by means of which motion is transferred from the vertical shaft 11, 11' and 11'' to the propeller wheels. Numerals 16, and 16' designate planes mounted with 25 in the air flues 8 and extending longitudinally forward and rearward from the propeller wheels, by means of which air planes, carrying pressure surface is added to the machine and are preferable in my device in 30 place of wings and side planes as in the construction of aeroplane type of machines and by means of which the carrying capacity of my machine is greatly increased. 17, designates the glass shields in the front end 35 of the machine for the protection of the operator. Numerals 18, 18' and 18'' designate forward steering planes which are pivotally mounted within the front concave end of the gas cylinder by means of pivot bearings 40 19, 19', 19''. 20, designates the rod connection, the upper portion of which is pivotally connected at the rear of the three front planes by means of pivot hinges 20', the lower end of said rod is pivotally connected 45 to rocker arm 21 which is mounted upon rocker shaft 21'. Numeral 22 designates the rod connection, one end of which is pivotally connected to the lower end of the rocker arm 21, the other end of said rod 50 is pivotally connected to the lower end of the operator's lever 23, by means of which connections the operator controls the tilting of the front planes 18, 18' and 18'', and by means of which the flying machine ascends 55 and descends and is controlled. Numeral 24 designates the rear vertical rudder pivotally mounted upon vertical shaft 24' at the rear end of the gas cylinder by means of pivot journals 25 and 26. Mounted on the 60 lower end of rudder shaft 24' is the arm 27 to the outer end of which is pivotally connected one end of the rudder operating rod 28, the other end is pivotally connected to the lower end of operating lever 29, and 65 by means of which the operator adjusts and

regulates the angle of the rear rudder which controls the direction of the machine to the right or left when flying. 30, represents the operator's seat from which the engine power transmission, and steering devices are all 70 decontrolled. Numerals 31 and 32 and 33 designate tubes the lower ends of which are securely fastened to the bottom of the gas cylinder and the upper ends of which are securely fastened to the bottom of their respective air flues forming passageway for 75 shafts 11, 11' and 11'' which transmit power to the propeller wheels within the air flues.

It will be observed that my flying machine is mounted upon wheels of the automobile 80 type, the bottom portion of the machine between the side frames is constructed in V shape and water tight, adapted to float upon the surface of water. It will be observed further that hinged at each side of the lower 85 frame work are planes 1' which raise and slant upward a limited distance when the machine is resting upon the water as indicated by the dotted line shown in Fig. 4. 90 1'' designates the slanting front end of the water tight compartment forming the bottom of the machine above the axle line.

It will be further observed that in the 95 operation of my machine when the propeller wheels are revolving at their normal speed the tendency will be to draw the air from the front of the machine at a rapid speed into the concave front end and through the front portion of the air flues, resulting in creating more or less vacuum in front of the 100 machine. The air is then forced rearward from the propeller wheels through the rear portion of the air flues and against the atmospheric pressure, thereby forcing the machine forward through the air.

Referring to Figs. 1 and 2 it will be observed that when flying and operating that by tilting the front planes 18, 18' and 18'' so that the outer edge of said planes are tilted downward the machine will descend and 110 when tilted upward the machine will ascend. It will also be observed that by swinging of the rudder at the rear end, the said flying machine can be directed to the right or left 115 at the will of the operator.

Referring to Fig. 4 it will be observed that in the event for any reason the machine is descending at a rapid speed the air gates 5 on each side of the machine will automatically swing upwardly thereby opening 120 the exhaust chamber, causing a rush of air from the outside to enter the exhaust chamber 4 which at once becomes in part a parachute having release valves on top through which a resisting air current will pass, thereby 125 providing added buoyancy to the machine while descending.

From the foregoing description, illustrations and described means for the operation of my improved flying machine, it will be 130

apparent that while the accompanying drawings fully illustrate what I believe to be the full embodiment of my invention it is not limited thereto but that various changes may be made in the construction and arrangement of parts and the transmission of power thereto without departing from the spirit and scope of the invention as defined in the pending claims.

19 Having fully described my invention, what I claim as new and desire to secure by Letters Patent is:—

1. A flying machine of the character described, including a main gas cylinder having an inverted concave head at the front end and an inverted straight head at the rear end of said gas cylinder, a supporting frame work rigidly attached to the lower portion of the gas cylinder, air flues mounted within said gas cylinder and extending longitudinally through the heads thereof, propeller wheels mounted within and near the center of said flues and means for transmitting motion to said propeller wheels, planes mounted crosswise within said flues and extending longitudinally forward and rearward from said propeller wheels the entire length of said flues substantially as described and specified.
2. A flying machine of the character described, including a main gas cylinder having an inverted concave head at the front end and an inverted straight head at the rear end of said gas cylinder, a supporting frame work rigidly attached to the lower portion of the gas cylinder, air flues mounted within said gas cylinder and extending longitudinally through the heads thereof, propeller wheels mounted within and near the center of said flues and means for transmitting motion to said propeller wheels, planes mounted crosswise within said flues and ex-

tending longitudinally forward and rearward from said propeller wheels the entire length of said flues, steering planes pivotally mounted within the front concave head of the gas cylinder and extending outwardly beyond said cylinder and means for tilting said planes for causing the ascent and descent of said flying machine, a vertical rudder mounted within the rear portion of said gas cylinder and extending outwardly therefrom and means for swinging said rudder for the purpose of directing the course of said flying machine while navigating the air as described and shown.

3. A flying machine of the character described, including a main gas cylinder having an inverted concave head at the front end and an inverted straight head at the rear end of said gas cylinder, a supporting framework rigidly attached to the lower portion of the gas cylinder, air flues mounted within said gas cylinder and extending longitudinally through the heads thereof, a combination hot air chamber and parachute mounted upon the upper portion of said gas cylinder and extending longitudinally the entire length thereof, having pressure release valves mounted upon the upper portion of said chamber, air gates pivotally hinged to the sides of the gas cylinder and which automatically open and close each side at the lower portion of the hot air chamber when said flying machine is ascending and descending as described and for the purpose specified.

In testimony whereof, I hereunto affix my signature.
